UNITED STATES PATENT OFFICE.

JOHN H. GILMAN, OF OTTAWA, ILLINOIS, ASSIGNOR TO KING & HAMILTON COMPANY,
OF OTTAWA, ILLINOIS, A CORPORATION OF ILLINOIS.

WAGON-DUMP.

1,078,670.

Specification of Letters Patent. Patented Nov. 18, 1913.

Application filed March 7, 1910. Serial No. 547,902.

To all whom it may concern:

Be it known that I, JOHN H. GILMAN, a citizen of the United States, and a resident of Ottawa, in the county of La Salle and

5 State of Illinois, have invented certain new and useful Improvements in Wagon-Dumps, of which the following is a full, clear, and exact specification.

My invention is concerned with wagon 10 dumps of the type in which the front wheels of the wagon are suspended from an overhead support, and is designed (1) to insure the accurate placing and retaining of the rear end of the wagon in its proper relation 15 to the cross conveyer while its contents are being discharged; and (2) to increase the stability of the structure where it is portable.

To this end my invention consists in certain novel combinations of elements which 20 will be fully described in the body of the specifications and particularly pointed out in the claims.

To illustrate my invention I annex hereto 25 two sheets of drawings in which the same reference characters are used to designate identical parts in all the figures, of which,—

Figure 1 is an end elevation of an indoor dump employing my invention; Fig. 2 is a side elevation of the same. Fig. 3 is a plan 30 view of the frame and tie rods pivotally connected thereto. Fig. 4 is a perspective view of my invention employed in the portable wagon dump; and Fig. 5 is a side elevation of the swinging frame, showing the 35 wheels resting thereon.

In carrying out my invention for indoor dumps I provide in it suitable means for winding up the flexible members (10), which may consist of ropes or chains, such, for instance, as the shaft (11) journaled in suitable bearings, and provided with the winding drums (12) upon which the chains (10) are wound as the shaft (11) is rotated by a suitable means, such, for instance, as a 40 chain (13), applied to the sprocket wheel (14), secured on the end of the shaft. Instead of terminating these chains (10) in rings, hooks or loops, as was the practice in the prior art, I secure them to the bails (15), which are preferably triangular in shape and may be made of one or two pieces of material as desired and which, as seen in Fig. 5, extends up above the plane of the tops of the front wheels of the wagon so as 50 to insure stability and prevent the possi-

bility of the frame tipping, as would inevitably occur with the connections herein-after described if they were omitted or did not extend upward as described.

The lower ends of the bails (15) are secured to the rectangular frame (16), which preferably consists of the two longitudinal members (17) and the two transverse members (18), the frame of course being of a suitable length and width to receive and support the two front wheels of an ordinary farm wagon. This frame, of course, may be composed of wood or of metal.

To prevent the shifting of the hind wheels of the wagon while the frame (16) is being raised with the front wheels of the wagon thereon, I pivotally connect preferably to each end of the frame (16) a tie rod (19), the other end of which is pivotally connected, preferably to the floor, where it is 70 an inside elevator, by any suitable means, such as the eye pieces (20); which are located at a point near where the hind wheels of the wagon rest when the front wheels are upon the frame (16). When the shaft (11) 75 is rotated to wind up the chains, it will be obvious that the tie rods (19) prevent the possibility of the frame (16) rising in a straight line and causing the rear wheels of the wagon to be misplaced, as the frame (16) 80 and accordingly the front wheels of the wagon must move through the arc of a circle preventing the rear end of the wagon from having any longitudinal movement. Where the frame (16) is used in an indoor 85 construction, the floor may be recessed as indicated in the dotted lines in Fig. 2, so that the frame in its lowermost position may rest in the recess, if desired, to prevent the jar, resulting from the front wheels of the 90 wagon being raised over frame (16) where it rests on the top of the floor.

In Fig. 4, I have shown my invention as applied to a portable wagon dump, adapted for use in connection with a portable elevator (21) and a cross conveyer (22). As is customary in this class of devices, the elevator, cross conveyer and dump are all driven from a single power shaft (23), which has suitable driving connections with the elevating chains and bars (24) and likewise suitable driving connections (25) with the cross conveyer (22) which is adapted to be moved in and out of position, so that when the rear wheels of the wagon rest on 105 110

the bottom cross piece (26), the tail end of the wagon is properly located to discharge into the cross conveyer (22) when it is placed at right angles to the shaft (23).

5 The frame work of the portable dump consists of the side frames (27), which are connected at the top by the top cross piece (28), and the base extensions (29) are preferably detachably secured to the bottoms of 10 the side frames, so that it can be transported more readily, and have their outer ends connected by the bottom cross piece at (26).

15 The braces (30), preferably detachably secured to the outer ends of the extensions (29) and toward the tops of the side frames (27), serve to add to the rigidity of the structure, the complete frame work thus being one that cannot be readily toppled over, especially when the stakes (31) are 20 driven in the ground to hold it in place. The extension (32) of the driving shaft is connected with suitable gearing (33) by which the flexible members, such as the chains, are wound and unwound by any desired mechanism, such, for example, as 25 shown in Figs. 1 and 2. The specific form of this gear 33 and its connections with the chains 10 form no part of my present invention, and any desired form may be employed, such, for instance, as those shown in 30 my application No. 673,466, filed January 25, 1912. In this form the chains (10) are likewise connected to the bails (15), which are in turn connected to the frame (16), 35 which has the tie rods (19) connecting it to the bottom cross piece (26) as before.

The operation of the portable form of my invention will, of course, be the same as that of the stationary form.

40 While I have shown and described my invention as embodied in the form which I consider best adapted to carry out its purposes, it will be understood that it is capable of modifications and that I do not 45 desire to be limited in the interpretation of the following claims, except as may be necessitated by the state of the prior art.

What I claim as new and desire to secure by Letters Patent of the United States is:

50 1. In a wagon dump, the combination with a framework, of a pair of flexible members suspended therefrom at a considerable height, means for winding up said members, rigid bails suspended from said members 55 at or above the level of the top of the front wheels of a wagon when they are unwound, a rigid wheel-supporting frame connecting the bottoms of the bails and upon which the front wheels of a wagon are adapted to rest, 60 and a pair of tie rods of a length substantially equal to the length of the wheel-sup-

porting frame pivoted at one end to the frame and at the other ends to the framework toward where the rear wheels of the wagon rest, said flexible members and tie rods constituting the only connections between the framework and the wheel-supporting frame and its bails, substantially as and for the purpose described.

2. In a wagon dump, the combination with a framework having bottom side pieces substantially of the length of a wagon, a bottom cross piece at the rear end, side frames, and a top cross piece at the top of the side frames and toward the front end, 75 of a pair of flexible members suspended from the top cross piece, means for winding up said members, rigid bails suspended from said members at or above the level of the top of the front wheels of a wagon when 80 they are unwound, a rigid wheel-supporting frame connecting the bottoms of the bails and upon which the front wheels of a wagon are adapted to rest directly beneath the top cross piece, and a pair of tie rods of a 85 length substantially equal to the length of the wheel-supporting frame pivoted at one end to the bottom cross piece and at the other ends to the adjacent corners of the wheel-supporting frame.

90 3. In a portable wagon dump, the combination with a frame having bottom side pieces adapted to be folded at the middle and when extended substantially of the length of a wagon, a bottom cross piece at 95 the rear end, side frames at the front end, a top cross piece at the top of the side frames, and detachable brace rods extending from the rear ends of the side pieces toward the tops of the side frames and connected 100 thereto, of a pair of flexible members suspended from the top cross piece, means for winding up said members, rigid bails suspended from said members at or above the level of the top of the front wheels of a 105 wagon when they are unwound, a rigid wheel-supporting frame connecting the bottom of the bails and upon which the front wheels are adapted to rest, and a pair of tie rods of a length substantially equal to the 110 length of the wheel-supporting frame pivoted at one end to the bottom cross piece and at the other end to the adjacent corners of the wheel-supporting frame.

115 In witness whereof, I have hereunto set my hand and affixed my seal, this 3rd day of March, A. D. 1910.

JOHN H. GILMAN. [L. S.]
